UNITED STATES PATENT OFFICE

LEIGH P. HOFF, OF PHILADELPHIA, PENNSYLVANIA, ASSIGNOR TO THE ALLEN-SHERMAN-HOFF COMPANY, OF PHILADELPHIA, PENNSYLVANIA, A CORPORATION OF PENNSYLVANIA

APPARATUS FOR BREAKING AND HANDLING SOLIDS

Application filed May 10, 1929. Serial No. 361,846.

This invention relates to an improved device for the disposition of solid materials.

More particularly it relates to a device for breaking up and disposing of furnace residues, distillation residues and the like.

It has been customary in the disposition of solid residues from a furnace to drop the same from the furnace hopper into a conduit through which the residues are conducted to a sump tank. The larger residues have been prevented from passing into the conduit from the furnace hopper by means of a grate and have been broken up manually or otherwise separately disposed of.

It is an object of this invention to provide a device for mechanically breaking up solid materials including solid residues of combustion to a size which will permit of their being removed by the use of fluid.

Still another object is to provide a grinding and compressing device for solid residues which device is provided with easily accessible replaceable wear parts.

It is a further object to devise means for removing furnace residues which saves considerable valuable head room under hoppers and furnaces and is also economical in operation, construction and maintenance.

Other objects will be apparent from the specification and from the accompanying drawings in which latter:

Fig. 1 is a longitudinal sectional view of the device;

Fig. 2 is a longitudinal section of a modification of the device, and showing associated parts.

Referring particularly to Fig. 1 of the drawings, the device comprises a receptacle 1 having an inlet hopper 2 adapted to receive incombustible residues from the discharge opening of a furnace bottom or hopper 3. A movable gate 4 controls the discharge of incombustible residues through the discharge opening. The receptacle can be disposed upon the boiler house floor, as shown and so associated with the hopper as to prevent escape of undesirable quantities of dust during the discharge of the residues from the hopper. The end 5 of the receptacle is provided with an outlet 6 which communicates with a

sluiceway or conduit 7. Liquid is adapted to be introduced into the sluiceway from nozzle 8 forming a conveyor system whereby the residues are conducted into sump tank 9.

The portion of the receptacle beneath the inlet hopper 2 is provided with a liner 10 removably disposed therein. The liner is preferably made of abrasion resisting metal and is sprung into positive engagement with the walls of the receptacle. A second liner 11 of similar material is detachably secured in the receptacle, one end thereof abutting the liner 10 and the opposite end abutting the end wall 5 of the receptacle.

Cutting means are disposed upon a shaft 12 which is mounted within the receptacle and is adapted to be rotated by a source of power (not shown). The cutting means comprises a plurality of collars 13 which are rigidly affixed to the shaft. Each collar carries a plurality of teeth 14 extending therefrom at an angle to the length of the collar and each tooth is semi-spirally shaped from its base to its tip, also the edges of the teeth are bevelled to increase their cutting ability. The edges of the teeth terminate in spaced relation to the ends of their respective collars.

Liner 10 is equipped with a series of teeth (11a) on one or both sides attached at an elevation of approximately the center line of the shaft and so spaced that the shaft teeth pass between them.

A helix is formed upon the shaft 12 within the liner 11 and is adapted to cooperate therewith to move the broken incombustible residues toward the discharge opening. The helix is formed by a plurality of collars 17 rigidly affixed to the shaft, each collar carrying a section 18 of a helix. When assembled with the helix sections in abutting relation the sections form a complete helix.

The broken incombustible residues are fed forwardly by the helix into the space between the end of the helix and the end wall 5 and are compacted in this space. Successive increments of the compacted residues are fed through the outlet 6 by means of a plurality of teeth 20 carried by a collar 21 which is rigidly affixed to the shaft 12.

In the operation of the device the incom-

bustible residues are dropped through the inlet hopper 2 into the receptacle. The drive shaft 12 is rotated in a clockwise direction as viewed from end 5 causing the rotating teeth 14 operating in connection with stationary teeth 11a to chip the residues into small pieces and at the same time, by virtue of the inclination of the teeth to effect a lateral movement of the pieces toward the helix. The broken pieces are conducted by the helix toward the end wall 5 and are fed by the teeth 20 through the outlet 6 into sluiceway 7 through which they are washed by liquid from nozzle 8 into the sump tank 9.

In the embodiment illustrated in Fig. 2a furnace 23 is mounted immediately above the boiler house floor 24. Residues are dropped from the hopper onto inclined feed plates 25 from which they are flushed by means of liquid from nozzles 25a through a grate 26 into a conduit 27 which is disposed beneath the boiler house floor. Liquid from a nozzle 28 flushes the residues through the conduit 27 into a sump tank 30 which can be disposed exteriorly of the boiler house. A discharge pipe 31 is provided to remove overflow water from the sump tank. A grinding device is disposed in the bottom of the sump tank and comprises a shaft 33 which is driven in rotation from the pulley wheel 34. A thrust bearing 35 prevents endwise thrust of the shaft. A plurality of collars 36 are disposed rigidly upon the shaft in abutting relation and carry grinding teeth 37 thereon. These rotating grinding teeth operating in conjunction with stationary teeth 37a serve to break up the residues and move them laterally toward the right as viewed in Fig. 2 as has previously been described. A helix 38 receives the broken ash and moves the same laterally into the space 39 between the end of the casing 40 and the end of the helix. Blades 41 disposed upon the shaft 33 tend to force the residues through opening 42 into a sump tank 43. Liquid such as water can be introduced into the upper portion of space 39 through a pipe 44 to wash the residues into tank 43. The mixture of residues and water can be pumped by pump 45 through pipe 46 into storage tank 47. A discharge conduit 48 is adapted to withdraw the water from the residues in tank 47 to sump tank 30.

While particular embodiments of the invention have been shown and described it will be understood that modifications can be made therein or other modifications made without departing from the spirit of the invention and it is not desired to limit the scope of the invention otherwise than is indicated by the accompanying claims.

What I claim is:

1. An apparatus for handling ashes from a fuel burning furnace comprising a receptacle adapted to receive such ashes, an annular extension communicating with the re-

ceptacle and having an outlet opening, a rotatable shaft disposed in said receptacle and extension, spaced means on the shaft in the receptacle for striking and breaking up ashes in said receptacle and advancing such material toward the extension when the shaft is rotated, means on the shaft in the extension for compacting and advancing ashes through said extension, and means at the outlet opening of the said extension for delivering the compacted ashes from said extension. 70

2. The apparatus set forth in claim 1, in which the spaced means on the shaft in the receptacle are spirally shaped sharp edged teeth. 80

3. The apparatus set forth in claim 1 in which the means on the shaft in the extension is a spiral conveyor. 85

4. The apparatus of claim 1 in which the means at the outlet opening of the extension for delivering the compacted ashes from said extension is a toothed member on the shaft. 95

5. The apparatus of claim 1 in which the means at the outlet opening of the extension for delivering the compacted ashes from said extension includes an inlet for fluid adjacent to the delivery end of the extension. 90

6. The apparatus set forth in claim 1 in which the receptacle is provided with a removable liner about and concentric with the shaft and open to permit ashes to enter the space between the shaft and liner. 95

7. The apparatus set forth in claim 1 in which the extension is provided with a removable liner about and spaced substantially equidistant from the compacting and advancing means on the shaft therein. 100

8. In an ash disposal system for a fuel burning furnace, the combination of a receptacle having an annular extension opening into the receptacle and having an outlet opening, rotatable means in the said receptacle an extension for advancing ashes from the receptacle into and through the extension while compacting the ashes in the extension, said rotatable means including a rotatable shaft disposed in said receptacle and extension and means on said shaft in said extension for advancing ashes therethrough, said ash advancing means stopping short of the outlet opening of said extension, means at the outlet end of the extension for feeding the compressed ashes from the extension, and means including a second receptacle operatively associated with the outlet end of the extension to receive ashes discharged therefrom and to mix the same with liquid for subsequent disposal. 110

9. Apparatus for handling ashes from a fuel burning furnace comprising a receptacle adapted to receive such ashes, an extension communicating with the receptacle and having an outlet opening, a rotatable shaft disposed in said receptacle and extension, means on the shaft in the extension for ad- 125

130

vancing ashes through said extension, said means stopping short of the receptacle outlet opening whereby the ashes are compacted in said extension, and means at the outlet opening of the said extension for delivering the compacted ashes from said extension.

In testimony whereof I hereunto affix my signature this 24th day of April, 1929.

LEIGH P. HOFF.
